UNITED STATES PATENT OFFICE

HAROLD J. BRUNK, OF CHICAGO, ILLINOIS, ASSIGNEE, BY MESNE ASSIGNMENTS, TO THE
C. F. PEASE COMPANY, A CORPORATION OF DELAWARE

ARC LAMP

Application filed September 28, 1927. Serial No. 222,537.

This invention relates to improvements in arc lamps.

The principal object of the invention is to provide an improved arc lamp adapted for general illumination and having also as one field of usefulness photographic work, such as blue printing, photo engraving and the like, and as another field of usefulness, therapeutic work.

10 In arc lamps as at present constructed, trouble is encountered as for example in blue printing, photo engraving and other photographic work, due to the fact that as the carbons are consumed the current decreases, thus lowering the temperature of the arc and changing the character of the light emitted by decreasing the actinic rays. Also the light flickers under these conditions and when the arc elongates to the breaking point, the light 15 is, of course, completely extinguished momentarily. Further difficulty is caused by the tendency of the so called "hot spots" of the carbons to travel around the points of the carbons thereby causing variations in light 20 and sometimes causing slight shadows to fall over the sensitized photographic material, thus rendering the work of a variable quality and the exposure more or less subject to guess work.

25 A further object of the invention is to overcome these difficulties by providing mechanism which will so regulate the movable or upper carbon as to prevent the breaking and sputtering of the arc and to stabilize the same.

30 An additional object is to provide an arc lamp, the movable parts of which operate with so little friction and of such uniform degree in nearly all positions that the lamp may be operated satisfactorily at a considerable angle from the vertical.

35 Further objects relate to various features of construction and arrangement of parts which will become apparent from a consideration of the following specification and accompanying drawings, wherein

40 Fig. 1 is a front elevation of an arc lamp embodying the present improvements;

Fig. 2 is a side elevation thereof;

45 Fig. 3 is a top plan view of the upper mechanism;

Fig. 4 is a diagrammatic view illustrating the circuits employed in carrying out the improvements; and

Fig. 5 is a top plan view of the stabilizing magnet and associated parts.

55 In the drawings, 10 is a suitable arc lamp frame having a suitable carbon holding member 11 at the bottom thereof for supporting the carbon 12. An upper carbon 13 is carried by a suitable clutch member indicated generally by the numeral 14 having a buffer spring 15 and a porcelain slide 16, which is guided in its vertical movement by the guides 17. The above described structure may be of standard construction and forms 60 no part per se of the present improvements.

Suitably carried by the frame 10 is an auxiliary frame 18, having a plurality of lugs 19 suitably spaced along the semi-circular upper edge 20.

70 Secured to the four right hand lugs, as viewed in Fig. 1, are a plurality of current responsive coils or coil sections 21. As shown in Fig. 5, these coils are connected with the main conductors 22 in series with the carbons and with the magnet coil 23 and with a suitable resistance 24.

75 A plurality of high resistance coils 25 are mounted on the left hand row of lugs in Fig. 1 and are shunted across the main line as shown in Fig. 5. The coils or solenoids 21 and 25 are stationary and have open centers through which an arcuate armature or core 26 is adapted to pass. Said armature is carried by a suitable pivoted frame 27 journalled 80 at 28-28, to a vertical standard 29. The frame 27 also carries a counter balance 30 on a threaded spindle 31 for counter balancing the weight of the parts which are very 85 nicely balanced and which turn with very little friction about the two journals.

90 The upper carbon is raised and lowered by the swinging movement of the frame 27 by means of a cross rod 32 on which is pivoted a depending bracket 33 at the lower end of which is an angularly disposed arm or clutch 34 with the usual ring at one end surrounding the upper carbon.

95 It will be seen that as the armature 26 moves through the coils, the frame 27 will be 100

rocked upon the pivots 28-28, thereby raising or lowering the bracket and clutch, and thus moving the upper carbon 13, which, together with the lower carbon 12 is preferably enclosed in a suitable globe 35. The parts are so balanced that the weight of the upper carbon is the only weight supported by the pivoted frame.

In operation, the series coils 21 tend to move the armature in a clock-wise direction, as viewed in Fig. 1, to raise the upper carbon, while the shunt coils 25 tend to move the armature in counter clock-wise direction to lower it. Assuming that no current is flowing and that the carbons are in contact, the immediate effect of turning on the current is to energize the series coil and raise the upper carbon a certain amount, thus establishing the normal arc. As the carbon points are consumed, the length of the arc is increased, its resistance also is increased with a resultant decrease of current in the series coil and an increase in the voltage across the arc.

Considering first the action of the series coils alone, a decrease of current therein will weaken them causing them to tend to decrease their pull on the core and on the upper carbon but nevertheless tending continually to raise said upper carbon. When this diminishing upward pull is eventually overcome by an increasingly effective weight, as in the prior practice, the carbon is lowered by said weight but the inertia of the weight frequently lowers the carbon to such a point that the clutch releases it and it drops, thus extinguishing the arc.

Considering the action of the shunt coils, as in the present case where the weight is dispensed with, as the normal arc lengthens due to consumption of the carbons, the voltage across the arc increases until at a predetermined voltage value the resistance is overcome and sufficient current flows through the shunt coils to energize the same and move the core in a direction opposed to the pull of the series coils. The pull of the shunt coils more than offsets the decreasing pull of the series coils, thereby lowering the upper carbon slightly, enough to restore the necessary balance and maintain the predetermined length of the arc. This is accomplished by virtue of the fact that as the upper carbon is being lowered, due to the differential action of the two coils, the decreased resistance of the arc causes an increased flow of current in the series coils whereby their pull eventually balances the pull of the shunt coils. This operation takes place upon very slight amperage fluctuations, due largely to the practical elimination of friction and the reduction of the weight to be lifted and of the inertia of the parts to a minimum, with the result that the carbons do not become separated a sufficient distance to break the arc, nor does the arc flicker, but burns steadily for hours.

To prevent the movement of the "hot-spots" of the arc around the points of the carbons, a magnet 23 is provided in series with the carbons for stabilizing the arc. The magnetic field created by the coil tends to blow the arc to the front side of the carbons and retains the same in such position, thereby preventing the objectionable shadows previously referred to.

The magnet coil 23 is so mounted as to permit considerable flexibility in its adjustment. It is mounted on a slotted vertical support 36 by means of a screw 37 whereby it may be raised and lowered. Said member may be swung about a horizontal pivot 38 at the lower end of an arm 39, the upper end of which may be adjusted back and forth in a horizontal slot in an arm 40 by means of a bolt 41, one end of said arm 40 being arranged to turn about a vertical pivot 42 at one end of a slotted arm 43 which latter is adjustable vertically in a slot in a bracket 44, the latter being arranged to swing on a vertical stud 45. With this arrangement the magnet coil may be swung, for example, to the dotted line position shown in Fig. 5, to deflect the arc forwardly. However, where a series of arc lamps in a row are employed as in blue print machinery, for example, the arc is influenced by various parts of the structure so that it may be necessary to adjust the different magnet coils to different relative positions in the case of the various lamps, in order that all of the arcs may be blown toward the front.

As a further refinement in the operation, the shunt coils 25 are shown in Fig. 4 as being connected individually by means of taps 46 to a switch 47 which may be mounted on any convenient part of the frame. When the lamp is assembled the switch is adjusted so as to utilize all four of the shunt coils, if necessary to the proper operation of the device. Due to variations in materials it may be necessary to utilize only three or a less number of the coils in any particular installation and the switch will therefore be adjusted accordingly. It will usually be left undisturbed after the initial adjustment except where variations in line voltage render further adjustment desirable.

With the adjustments described it is possible to adjust two or more arc lamps so that they will emit light of the same value for considerable intervals of time, even though said lamps are mounted in a row whereby each influences the other.

The provision of individual series and shunt coils is better than the provision of a single coil having both series and shunt windings for the reason that with the arrangement shown, eddy currents are eliminated and overheating prevented. A further cooling advantage results in the provision of sectional shunt and series coils as the

eddy currents are substantially eliminated and the ventilation of the individual sections is increased.

Surrounding the operating mechanism is a shield 48 which may be of wire or expanded metal to protect the same against damage and to protect the operator against injury.

The stability of the lamp described herein is dependent on a number of factors. First, 10 friction is substantially eliminated since there are but two areas in frictional engagement in the lamp mechanism, i. e. the small pins and bearings about which the frame turns. It will be seen that the armature does not make contact with the magnet coils but 15 clears the same at all times. With the carbon removed from the lamp, the mechanism is perfectly balanced and is so sensitive that it will move at the slightest change of arc voltage. Second, the arrangement whereby the 20 sections of the shunt coils may be varied is important as the adjustment of the same by means of the switch permits compensation for variations that necessarily occur within the coils when they are wound and in the 25 metal of the armature itself. This variable shunt coil is of great benefit in balancing the lamp in each particular installation, as the amperage across the arc itself can be changed 30 as this shunt coil is varied, permitting not only the lamp itself to be balanced, but variations in the line voltage to be compensated for. For example, if three sections of the 35 shunt coil are in circuit, and the upper carbon moves irregularly due to the arc voltage being a little too high, by changing the switch point to include four coils in the circuit, the greater pull created by the extra coil helps to shorten the arc and bring about 40 a lower voltage with a stable condition. The decreased voltage results in an increased amperage, the wattage across the arc remaining the same in all cases.

It is well known that nearly all of the effective light in a direct current arc lamp is received from the crater of the positive carbon, and in the case of alternating current considerably more than one-half of the effective light is received from the crater or two 50 "hot-spots", one on each carbon. Some authorities state that the ratios are 90% in the case of direct current and over 60% in the case of alternating current. In view of these facts the advantage of having the "hot-spots" confined to the front of the carbons is 55 obvious, and by means of a stable arc the temperature remains substantially constant, thereby insuring light of uniform value for photographic purposes at all times, due to 60 the very slight and unchanging friction and the use of two pivots for the oscillating frame. In this connection, the use of the terms "above" and "below" and similar terms are understood to be used in a relative sense 65 without necessarily implying an exact ver-

tical arrangement of the carbons and associated parts. The lamp also operates satisfactorily in inclined position.

Although I have shown certain features of my improvements combined in a single structure, it will be apparent that some of them are capable of use independently of others and that various changes may be made in the design and arrangement of parts illustrated herein without departing from the spirit of the invention.

What I claim is:

1. An arc lamp having an adjustable carbon and a stationary carbon, a fixed open center coil in series with said carbons, a 70 fixed open center shunt coil across the same, a single arcuate core passing through both of said coils, and means for transmitting motion from said core to said adjustable carbon, said core and said means being balanced about a pivotal support, said shunt coil tending to move said core in a direction to reduce the arc gap, and said series coil opposing such movement whereby fluctuations in voltage and current values due to a slightly increased gap between the carbons will 80 reduce the effectiveness of the series coil on the core and permit movement of the latter by the shunt coil in a direction to reduce the gap, thus insuring a stable arc. 85

2. Carbon adjusting mechanism for an arc lamp comprising an armature operatively associated with the adjustable carbon, and balanced to carry only the weight of said carbon, a coil for said armature in series with 100 the two carbons, a differential shunt coil adapted to move said armature in a direction to reduce the arc gap upon an increase in the voltage across the arc above normal, said shunt coil comprising a plurality of 105 tapped sections, and a switch for cutting out one or more of said sections from the shunt circuit.

3. An arc lamp comprising a lower and an upper carbon, a fixed current responsive 110 coil, a fixed voltage responsive coil and armatures therefor mechanically connected to said upper carbon only, said coils being arranged to act differentially whereby an increase in the length of the arc weakens said current 115 coil and, above a predetermined value, strengthens said voltage coil, said mechanical connections comprising a support having a single pivoted axis to minimize friction and to provide a balanced arrangement, thus 120 insuring stability of the arc.

4. An arc lamp comprising a lower and an upper carbon, a current responsive coil and a voltage responsive coil mechanically connected to said upper carbon only and arranged to act differentially whereby an increase in the length of the arc weakens said current coil and strengthens said voltage coil, said mechanical connections comprising 125 a core and a frame therefor having a single 130

pair of pivotal supports, said frame and associate parts being normally balanced about said pivotal support when said upper carbon is removed, adjustable magnetic means for blowing the arc to the front of the carbons and means for varying the normal amperage of said arc to insure uniform light from the same.

5. An arc lamp comprising a fixed carbon 10 and an adjustable upper carbon, a ring clutch for the latter, a supporting frame above said carbons, an oscillatable frame pivoted to said supporting frame and connected to said clutch, a group of series coils 15 arranged radially with reference to said pivoted support and at one side of said oscillatable frame, a group of shunt coils also radially arranged with reference to the same axis, an arcuate core passing through all of said 20 coils, brackets on said oscillatable frame by which said core is carried and a switch for varying the number of shunt coils in circuit.

6. An arc lamp comprising a vertical frame, a rectangular frame, a pair of pivotal 25 supports connecting the two, a curved frame secured to said vertical frame and having a series of lugs thereon, a plurality of coils each mounted on one of said lugs in radial position with reference to the axis of said 30 pivots, a single arc shaped core passing through all of said coils, an adjustable weight at one end of said rectangular frame, a depending link at the other end thereof, a carbon holding clutch secured to said link 35 and a switch connected to certain of said coils.

In testimony whereof, I have subscribed my name.
